UNITED STATES PATENT OFFICE.

LYMAN BARUCH POPE, OF HAVERHILL, MASSACHUSETTS.

HEEL-SHANK-SHAPING MACHINE.

Application filed December 7, 1927. Serial No. 238,365.

This invention relates to machines for finishing Louis and similar heels and particularly for shaping the shank portion of such a heel, or that portion which extends forward from the breast of the heel toward or along the shank of the shoe. The invention has for its general object to provide an improved mechanism of the type described in a co-pending application, Serial No. 59,329, filed September 29, 1925, for shaping this portion of a heel blank.

The more particular objects of the invention will be best understood from the following description of a preferred embodiment thereof illustrated in the accompanying drawings. It will be understood, however, that the particular constructions and operations described and shown have been chosen for illustrative purposes merely and that the invention as defined by the claims hereunto appended may be otherwise embodied without departure from its spirit and scope.

In the drawings:

Fig. 1 is a top plan view of the machine showing, partly in section, a heel blank in the work carrier prior to being turned into operative engagement with the shaping tool;

Fig. 2 is a similar view showing the work carrier turned to bring the heel blank into operative engagement with the tool;

Fig. 3 is a side elevation of the work carrier, with its mounting and associated parts, looking in the direction of the arrow in Fig. 1;

Fig. 4 is a vertical section taken on the line 4—4 of Fig. 3.

Fig. 5 is an end elevation looking from the right in Fig. 3 with the work carrier turned in a position to discharge the shaped work;

Fig. 6 is a detail view in elevation and partly in section of the detachable unitary work carrier;

Fig. 7 is a vertical section and Fig. 8 is a front elevation of a heel blank;

Fig. 9 is an elevational view of the improved cutter of the invention; and

Fig. 10 is a diagrammatic view showing the operative relation of the heel and the cutter.

The method and machine of the invention are adapted for use in connection with heels of a wide variety of forms. A typical heel

of the type to which the invention is applicable is shown at A in Figs. 7 and 8 and is shaped in the manner described in the above mentioned co-pending application.

In the machine illustrated a shaping tool or cutter B, the novelty of which will be referred to hereinafter, is suitably mounted on the end of a shaft 15 provided with a pulley 16 by which power may be applied from any suitable source through a belt 17. The shaft 15 is suitably journalled in a head 18 on a table 19. The heel blank A is supported in a work carrier, hereinafter described, which is eccentrically mounted on a shaft 20, said shaft being journalled in suitable bearings in a mounting on the table 19 and being provided at its outer end with a crank or other suitable operating member 21 by means of which it can be turned conveniently to swing the heel blank A past the tool B. The mounting for the shaft 20 comprises a support or carriage 38 adjustable in the direction of the axis of the shaft 20 by a manually operated adjusting screw 39 in a guide 40 on a second carriage 41. The carriage 41 is adjustable in a direction transverse to the axis of the shaft 20 by a manually operated adjusting screw 42 on a guide 43 secured to the table 19 by a clamp comprising a threaded stem 44 extending through an enlarged opening (not shown) in the table and provided on the underside of the latter with a threaded hand operated nut 46 (as more fully described in the above mentioned co-pending application) thereby providing a substantially universal bodily as well as an angular adjustment of the work carrying head as a whole.

In accordance with one feature of the invention the work carrier is provided as a detachable unit mounted upon the shaft 20 and comprising a head 50 (Figs. 4 and 6) provided with guiding surfaces 51 to receive a pair of spaced uprights 52 extending from a work holder 53 in angular relation thereto. The lower extremities of the uprights 52 are connected by a cross member 54 in which is provided a threaded opening 55 to receive a micrometer adjusting screw 56, the end of which is swivelled in the head 50 but held against longitudinal movement therein. One end of the head 50 is provided with a reduced portion 58 on which a substantially

circular template 59 is mounted and which is adapted to receive the heel seat engaging portion of the heel blank. The head carrying the work holder 53 and the template 59 5 is mounted upon the shaft 20 and clamped between the collars 60 and 61 by a nut 62, rotation thereof relative to the shaft 20 being prevented by a key 63 in the shaft engaging a slot 64 in the head. 10 The work holder 53 is provided with a clamp by means of which the heel blank A may be detachably secured thereto, said clamp comprising a pair of adjustable and movable clamping members 66 and 67. The 15 clamping member 66 (Fig. 1) comprises a dog pivoted at 69 to a slide 70 laterally adjustable on the plate or work holder 53 and secured in adjusted position thereon by a screw clamp 71 adapted to engage either of 20 the threaded holes 72 in the work holder. The clamping member 67 is pivotally mounted upon a slide 75 guided in a slot 76 in the work holder 53 and is provided with an extended angular free end 77. A micrometer 25 adjusting screw 79 is rotatably mounted in a bar 80 secured to the work holder and engages a threaded opening in the slide 75 thereby enabling the slide 75 and clamping member 67 to be adjusted to properly position 30 different types and sizes of heel blanks. The clamping member 67 is held in engagement with the heel blank A by a spring 81 extending between the angular free end 77 and an arm 82. The arm 82 is adjustably 35 secured to the work holder 53 by screws 84 in the holder passing through a slot 83 in the arm thereby enabling the tension of the spring to be adjusted. The tendency of the spring 81 to close the clamp 67 is limited 40 by a stop 85 adjustably mounted on the work holder 53.

The movable clamp 67 is held in opened or work receiving position when the work holder 53 is in work receiving position by 45 a suitable member, such as a roller 87, mounted in a block 88 provided with a depending guide 89 adapted to engage the edge of an arm 90 adjustably mounted upon the carriage 38 by screws 91 passing through 50 slots 92 in the arm 90. The position of the block 88 upon the arm 90 may be adjusted by a micrometer adjusting screw 94 rotatably mounted in a bracket 95 secured to the arm 90 and engaging a threaded hole in the 55 block. The block 88 may be secured in its adjusted position by a bolt 96 in the arm 90 passing through a slot 97 in the block.

A stop 98 is mounted on the arm 90 in the path of the movable clamp 67 to engage 60 the elbow 99 thereof, when the work holder has been turned and after the heel blank has been shaped by engagement with the tool B, to open the clamp 67 against the tension of the spring 81 and permit discharge of the 65 heel blank. In order to relieve the tension

upon the spring 81 a stop 100 is adjustably mounted upon the work holder 53 to engage the free end 77 of the clamp 67 and limit the opening movement thereof.

As described in the above mentioned co-pending application the machine may be provided with an adjustable breast gauge 101 to square the breast of the heel with respect to the shaping tool and to fix the position of the shank with reference to the template 59. As also described in the said co-pending application, in order to permit swinging of the work holder from the upper work receiving position shown in Figs. 1, 3 and 4 past the tool as shown in Figs. 2 and 5 without interference on the part of the gauge, the shaft 20 is provided with a cam 102 which cooperates with a fixed cam follower 103 on the carriage 38 so that as the work holder is turned out of its work receiving position the shaft 20 will move longitudinally toward the tool and when said work holder is returned to said position the shaft will be moved longitudinally in the opposite direction to bring the work holder in proper position for cooperation with the gauge. In accordance with the present invention, in order further to fix the work receiving position of the work holder the portion of the head comprising the collar 60 is provided with a shoulder 105 adapted to be engaged by a sliding pin 106 guided in a suitable opening 107 in the carriage 38 and preferably pressed outwardly by a spring 108.

In accordance with another feature of the invention an improved cutter is provided comprising a substantially cylindrical head or blade holder 110 provided with one or more slots or kerf 111, preferably extending into the holder 110 from the periphery thereof in a non-radial direction (as best seen in Fig. 9). A parallel slot 112 is provided near each slot 111, forming a clamping portion 116 between the slots which is adapted to be forced against a blade 113 in the slot to clamp said blade in the head. For this latter purpose opposite sides of the slots 112 are provided with complementary threaded enlargements 114 to receive wedge screws 115 which force the clamping portions 116 of the holder away from the main body thereof and against the blades.

In operation the heel blank A is placed upon the work holder against the clamp 66 and gauge 101. The work holder is then rotated past the cutter by turning the crank 21 in the course of which the cam 102 operates to move the blank away from the gauge 101, and the clamp 67 is released from the roll 87 and brought against the work to hold the same against the clamp 66. After the work has passed the cutter, the elbow 99 engages the stop 98 to release the clamp 67 and discharge the work. The work hold-

er is then returned to its original position by turning the crank 21 in the opposite direction, the clamp 67 being held against excessive movement by engagement with the 5 stop 85.

Heretofore in shaping heels the shaping tools often caused the edge of the heel blank to become torn at the side when the cutter leaves the work. In accordance with the 10 present invention this difficulty is minimized by the provisions of the invention whereby the cutter and the work holder are rotated in opposite directions so as to cause the work and the working face of the cutter to travel 15 in the same direction at their points of engagement. By such provisions the relative speed of travel of the cutter and work is reduced at the time the cutter leaves the work and assists in minimizing danger of the 20 work being torn.

What I claim is:

1. In a heel shank shaping machine, in combination, a shaping tool, a work carrier, and a shaft on which said work carrier is 25 mounted, said shaft being rotatable to swing said work carrier past said tool, said work carrier comprising a head detachably mounted on said shaft, a template detachably mounted on said head and having a curved 30 periphery concentric with said shaft, and a work holder adjustable on said head in a direction transverse to said shaft.

2. In a heel shank shaping machine, in combination, a shaping tool, a work carrier, 35 and a shaft on which said work carrier is mounted, said shaft being rotatable to swing said work carrier past said tool, said work carrier comprising a head detachably mounted on said shaft, a template detachably 40 mounted on said head and having a curved periphery concentric with said shaft, guides on said head extending in a direction transverse to said shaft, a work holder mounted in said guides, and a micrometer adjusting 45 screw in said holder for positioning the same as required.

3. In a heel shank shaping machine, in combination, a shaping tool, a work holder, a shaft carrying said work holder which is 50 rotatable to swing past said tool, a slide carried by said holder, a work engaging clamp pivotally mounted in said slide, and a micrometer adjusting screw adapted to move said slide to position said clamp as 55 required.

4. In a heel shank shaping machine, in combination, a shaping tool, a rotatable shaft, a mounting for said shaft, a work holder carried by said shaft, an adjustable 60 slide carried by said holder, a spring pressed work engaging clamp pivotally mounted in said slide, an adjustable arm fixed relative to said mounting, a stop on said arm positioned to engage and open said clamp to discharge work, and an adjustable stop on 65

said holder limiting the opening movement of said clamp.

5. In a heel shank shaping machine, in combination, a shaping tool, a rotatable shaft, a work holder carried by said shaft, 70 a slide carried by said holder, a work engaging clamp pivotally mounted in said slide, adjustable means for locking said slide in a given position upon said holder, and an adjustable member for holding said clamp 75 open when said work holder is in work receiving position.

6. In a heel shank shaping machine, in combination, a shaping tool, a rotatable shaft, a work carrier including a head 80 mounted on said shaft and a work holder mounted on said head, a slide carried by said holder, a work engaging clamp pivotally mounted in said slide, adjustable means for locking said slide in a given position upon said holder, and an adjustable member for holding said clamp open when said work 85 holder is in work receiving position.

7. In a heel shank shaping machine, in combination, a shaping tool, a rotatable 90 shaft, a work carrier including a head mounted on said shaft and a work holder mounted on said head, an adjustable slide carried by said holder, a work engaging clamp pivotally mounted in said slide, said 95 head having a shoulder, and a fixed pin engaging said shoulder to limit movement of the work holder into work receiving position.

8. In a heel shank shaping machine, in combination, a rotatable shaft, a mounting for said shaft, a work holder carried by said shaft, an adjustable slide carried by said holder, a work engaging clamp pivotally mounted in said slide and having an angular 100 free end, an adjustable arm fixed relative to said mounting, and a roller carried by said arm and positioned to engage the angular end of said clamp to open the same when said holder is in work receiving position. 105

9. In a heel shank shaping machine, in combination, a shaping tool, a rotatable shaft, a mounting for said shaft, a work holder carried by said shaft, an adjustable slide carried by said holder, a work engaging 110 clamp pivotally mounted in said slide and having an angular free end, an adjustable arm fixed relative to said mounting, a block slidably mounted on said arm, a micrometer adjusting screw for positioning said block 115 on said arm, and a roller mounted in said block to engage the angular free end of said clamp to open the same when said holder is in work receiving position.

10. In a heel shank shaping machine, in combination, a shaping tool, a rotatable shaft, a work holder carried by said shaft, a work engaging clamp pivotally connected to said holder and having an angular free end, an adjustable arm on said holder, a 120 125

spring secured to said arm and connected to the angular free end of said clamp to press the latter against the work.

11. In a heel shank shaping machine, in combination, a shaping tool, a work holder, a shaft carrying said work holder which is rotatable to swing said holder past said tool,

a slide carried by said holder, a pair of adjustable work engaging clamps one of which is pivotally mounted in said slide and 10 an adjusting screw adapted to move said slide to position said clamp as required.

In testimony whereof I affix my signature.
LYMAN BARUCH POPE.
